Primary Examiner — Paula Greene(74) *Attorney, Agent, or Firm* — Birch, Stewart, Kolasch & Birch, LLP(57) **CLAIM**

The ornamental design for a small speaker unit, as shown and described.

DESCRIPTION

FIG. 1 is a perspective view of the small speaker unit;
 FIG. 2 is a rear view of the small speaker unit;
 FIG. 3 is a front view of the small speaker unit;
 FIG. 4 is a right side view of the small speaker unit;
 FIG. 5 is a left side view of the small speaker unit;
 FIG. 6 is a top side view of the small speaker unit; and,
 FIG. 7 is a bottom view of the small speaker unit.
 The broken lines form no part of the claimed design.
